UNITED STATES PATENT OFFICE

2,476,248

ELECTRICAL PRECIPITATOR

Kenneth W. MacKenzie, Newton Highlands,
Mass., assignor to Raytheon Manufacturing
Company, Newton, Mass., a corporation of
Delaware

Application November 30, 1946, Serial No. 713,221

7 Claims. (Cl. 183—7)

1

This invention relates to electrical precipitators for electrically separating dust, smoke, and other impurities from air, and more particularly to an electrical precipitator of the type in which the air to be purified is first ionized in an ionizing zone and thereafter passed through a collecting zone wherein the dust particles are collected.

It is among the objects of the invention to provide an electrical precipitator of the type described which is suitable for domestic purposes, such as for purifying the air supply for a home, large room or office.

It is a further object of the present invention to provide a self-contained unit which may be readily installed and conveniently serviced.

It is a further object of the invention to provide, in a unit of the type described, a construction in which the dust collecting elements may be cleaned or washed in situ, so that the necessity for removing the dust collecting elements for the purpose of cleaning is avoided.

Other objects and features of the invention will be made fully apparent to those skilled in the art from a consideration of the following detailed description taken in conjunction with the accompanying drawing in which:

Fig. 1 shows a front elevation of the precipitator unit with a portion of the casing removed to show internal construction;

Fig. 2 represents a section taken on the line 2—2 of Fig. 1;

Fig. 3 represents a section taken on the line 3—3 of Fig. 2;

Fig. 4 shows a plan view of one of the walls of the ionizer and collector plate assembly; and

Figs. 5, 6, 7, 8, and 9 show plan views of the various collector plates used in the collector plate assembly.

Referring to the drawing, reference numeral 12 indicates a casing for housing all of the elements of the precipitator including a unitary ionizer and collector plate assembly, indicated generally at 13. The ionizer and collector plate assembly is supported on internal shoulders provided by the angle irons 14 and 15 which are welded to the internal wall of the casing 12. The casing 12 is provided with a removable front panel or door 17 which in this instance extends across the entire front face of the housing 12 from a level below the angle irons 14 and 15 to the top of the housing, and is hinged at 18 as shown in Fig. 3.

The ionizer and collector plate assembly comprises a pair of end plates 19 and 20 which are supported on the ledges provided by the angle irons 14 and 15 and which end plates in turn sup-

2

port the entire ionizing and collector plate assembly as a unitary structure.

The ionizing means comprises a plurality of fine wire electrodes each of which lies between and extends parallel with two surface electrodes, which surface electrodes are preferably formed integrally with certain of the charge plates of the collector plate assembly in a manner to be described. The fine wire electrodes of the ionizing means are mounted upon a framework supported by four insulators 22, two of which insulators are mounted at the upper end of each of the end plates 19 and 20. The charged plates of the collector plate assembly are supported from 15 the end plates 19 and 20 through insulators 23 in a manner which will hereinafter be more fully described.

The framework for supporting the fine wire electrodes of the ionizing means comprises a pair of angle irons 24 and 25 secured adjacent to their ends to the insulators 22, a pair of electrode supporting angle irons 26 and 27 which are welded to the angle irons 24 and 25 at the outer ends thereof, and an angle iron 28 welded at each end 25 thereof to the angle irons 24 and 25 at points intermediate the length thereof and extending parallel to the angle irons 26 and 27. Additional angle irons 29, 30, and 31 extending parallel to the angle irons 24 and 25 and welded to the angle irons 26, 27, and 28 may be added to give the framework additional rigidity. A plurality of pins 33 for supporting the fine wire electrodes 34 project downwardly from each of the angle irons 26 and 27 of the framework, which pins are secured in regularly spaced openings in the angle irons 26 and 27, each pin being secured by means of two nuts 35, one on each face of the horizontal side of these irons. The nuts 35 coact with threaded portions of the upper ends of the pins 33 to rigidly secure the pins in proper adjusted position. The lower end of each of the pins 33 is provided with a notched portion 36, and the pins are sufficiently resilient to permit the fine wire electrodes 34 to be held under some tension when looped portions at the ends of the wire are secured in the notches 36. The angle iron 28 as shown in Fig. 2 supports a plurality of hooks 37, each of which is spaced in alignment with two of the coating pins 33. Each of the hooks 37 engages a fine-wire electrode 34 at a point about midway of the length of the wire. By this construction vibrations of the fine-wire electrodes which might result from the application of a pulsating potential thereto are damped out.

The collector plate assembly comprises a plu-

rality of spaced parallel plates, alternate of said plates being charged to a potential of the opposite polarity to that of the fine wire electrodes 34, and the intervening plates being grounded. The support and arrangement of these plates will now be described. The end plates 19 and 20, one of which 19 is shown in Fig. 4, are provided with a plurality of relatively small openings 38. In this instance six of the small openings 38 are provided in each of the end plates, and these are adapted to accommodate a similar number of rods 39 which extend from one of the end plates to the other and are provided with threaded portions at the outer ends thereof, which threaded portions project through the openings 38 in each of the plates and are secured thereto by means of paired nuts 39 which engage the inner and outer faces respectively of each of the end plates to provide a rigid structure and maintain said end plates in a proper spaced parallel relation. The end plates 19 and 20 are also provided with a plurality of relatively large openings 48. In this instance five of the openings 48 are provided and are so spaced and of sufficient diameter to permit an insulating clearance between the outer ends of a corresponding number of rods which support the charge plates in a manner to be described. End plates 19 and 20 are also provided with small openings 41 at the upper ends thereof to facilitate the fastening of the insulators 22 to the end plates. Small openings 42 are also provided to facilitate the securing of the insulators 23 to the end plates.

Next adjacent each of the end plates 19 and 20 is an electrode-carrying plate 44. The plates 44 constitute two of the charge plates. Each carries at its upper end a curved portion 45 formed integrally with the plate. The axis of curvature of the upper portion 45 lies in the same plane and parallel to the fine wire electrodes 34, portion 45 providing a curved surface electrode coaxing with the outermost of the fine wire electrodes. The upper projecting curved portion 45 and each of the plates 44 are provided with a pair of openings 46 to permit the uppermost of the insulators 23 to pass through the plate with a small clearance therebetween. Each of the plates 44 is also provided with cut-out portions 47 and relatively large openings 48, which cut-out portions and openings permit the rods 39 and the spacing bushings thereon to pass adjacent to and through the plate with an insulating clearance therebetween. Each of the plates 44 is also provided with five relatively small openings 49 corresponding in position to that of the large openings 48 in the end plates 19 and 20. The openings 49 accommodate the threaded ends of a plurality of rods 50 for supporting the charge plates. These rods project through each of the plates 44 and are secured by nuts 51 engaging the outer faces of the plates 44 at the openings 49. The opposite faces of the plates 44 are engaged at the openings 49 by spacing bushings on each of the rods 50 extending to the next succeeding of the charge plates, and maintaining said next succeeding charge plates in proper spaced and parallel relationship relative to the plates 44.

The plates next adjacent to the plates 44 constitute two of the ground plates 54 which are constructed as shown in Fig. 6. These plates are of slightly greater length than the plates 44 and are provided with a pattern of small openings 38 corresponding in number and position to the openings 38 in the end walls 19 and 20. These relatively small openings 38 are of sufficient diam-

eter to permit the rods 39 to pass therethrough but without substantial clearance. These plates are thus directly supported from the end walls 19 and 20 by the rods 39 and are thus electrically connected to the end walls 19 and 20 and are hence maintained at ground potential. The plates 54 are maintained in proper spaced relation to the end walls on one side and to the next succeeding of the ground plates on the other side by means of spacing bushings on the rods 39 which engage each face of the plate 54 at the openings 38. These spacing bushings pass through the openings 48 in the adjacent plates 44 and through the cut-out portions 47 with a sufficient clearance to provide an insulating space therebetween. The plates 54 are also provided with a pattern of relatively large openings 40 and corresponding in size and position to the openings 48 in the end walls 19 and 20. These openings are sufficiently large and so placed that the supporting rods 50 which carry the charge plates together with the spacing bushings thereon may pass freely therethrough with an insulating space therebetween.

The plates 56 next adjacent the plates 54 constitute charge plates and are constructed as shown in Fig. 7. These plates are similar in construction to the plates 44 except that the electrode portion 45 is omitted. Otherwise the plates contain a pattern of five openings 49 corresponding in size and position to the openings 49 in the plate 44 and having the same purpose of supporting these plates from the rods 50. The plates 56 are also provided with the relatively large openings 48 and cut-out portions 47 to permit the passage therethrough of the supporting rods 39 together with the spacing bushings thereon.

The plates 54 and 56 alternate throughout the length of the collector plate assembly except that two of the charge plates at a short distance from each end of the collector plate assembly are constructed as shown at 58 in Fig. 8. These plates are identical with the charge plates 56 except that they are provided with projecting tabs 59 at each corner thereof, which tabs are provided with small openings 60 to permit the plates 58 to be secured at each corner to the insulators 23. Thus instead of being supported by the rods 50 which pass through the small openings 49, these plates are supported by the insulators 23 and in turn provide a support for the rods 50 and the remainder of the charge plates supported by these rods. Thus there is no other support for the charge plates through which electrical losses could occur. Also those of the charge plates which lie in a plane midway between any two of the fine wire electrodes 34 are constructed as shown at 62 in Fig. 9. These plates are identical with the other of the charge plates 56 except that they are provided at their upper ends with a curved surface electrode 63 which projects upwardly between any two of the fine wire electrodes 34. As seen in Fig. 1 the center of curvature of the upper portion of these electrodes lies in a vertical plane including the fine wire electrodes. The electrode portions 63 are shaped to present a streamline to the flow of air through the precipitator, the air intake being indicated at 65 and the air flow being downwardly through the unit to be discharged from the lower end thereof at 66.

In operation the fine wire electrodes 34 may be charged to a high positive potential, for example 6 kv. from any suitable source for example by an electrical circuit such as disclosed in my co-pending application, Serial No. 692,893, filed

August 24, 1946. The electrical connection to the fine wire electrodes may be made to any point on the supporting framework which is otherwise insulated by the insulators 22. The charge plates of the collector plate assembly and hence the electrodes 45 and 63 are connected to the opposite terminal of the source and hence are charged to a negative potential of 6 kv. The potential between the fine wire electrodes 34 and the relatively large surface electrodes provided by the portions 45 and 63 is thus 12 kv. which is sufficient to produce an ionizing discharge between the fine wire electrodes and the surface electrodes 45 and 63. All of the air passing through the unit must thus pass through the ionizing discharge prior to passing through the collector plate assembly. The potential difference between the charge plates and the ground plates is 6 kv. which is insufficient to cause ionizing discharges between the plates but sufficient to cause the charged dust and smoke particles to be collected thereon. In order to prevent any of the air from passing between the upper end of the electrodes 45 and the adjacent end walls 19 or 20 from which said electrode must be spaced, ledges 64 formed by angle irons welded on the end walls 19 and 20 may be provided to deflect any air, that might otherwise flow along the interior surface of the end walls, into the space between the electrodes 45 and the adjacent fine wire electrodes 34. The electrical connection for the charge plates and the curved surface electrodes may be made to any one of these charge plates or conveniently to one of the projecting electrodes 45 or 63. Upon disconnecting the two electrical connections, one to the fine wire electrodes 34 and the other to the charge plates, the entire ionizing and collector plate assembly may be removed as a unit through the front door 17 for servicing and repair.

The substantially streamlined contour presented by each of the electrodes 63 in the direction of gas flow and by the interior surface of the electrodes 45 avoids the formation of eddy currents in the region behind the electrodes and thus permits a more uniform distribution of the air to the spaces between the collector plates than is possible where purely cylindrical electrodes are used.

The streamlined contour presented by the surface electrodes 63 of the ionizing means also has the effect of minimizing the deposition of solid impurities from the air upon the surfaces participating in the ionizing discharge. Where purely cylindrical surface electrodes are used in this position there is a tendency for substantial deposits of impurities to build up in a short time upon the surface electrodes, particularly on the downstream sides thereof and to a lesser extent on the areas adjacent the fine wire electrodes and on the upstream sides of the surface electrodes. Such deposits on the surface electrodes of the ionizing means are objectionable in that alterations in the nature and size of the surface electrodes alter the characteristics of the ionizing discharge. I have found that by streamlining the surface electrodes 63 in the manner shown, such depositions on all portions of the surface participating in the ionizing discharge are greatly reduced. This is believed to be due to the fact that in prior constructions the contour of the surface electrodes has introduced a substantial amount of turbulence into the air stream. This turbulence acting in conjunction with the electrical attraction between the ionized particles and the surface electrodes has tended to throw large

quantities of the impurities onto the electrode surface where it was deposited. By the improved construction of the surface electrode, the force of electrical attraction alone tends to move the charged particles in the direction of the surface electrode. Since the particles are swept downwardly in a uniformly expanding air column, they do not come onto contact with the streamlined surface until they reach a zone much farther down in the air stream. The particles are thus carried beyond those portions of the surface area participating in the ionizing discharge and the ionizing surfaces remain substantially unaltered over relatively long operating periods.

In order to avoid the necessity for removing the ionizing and collector plate assembly for the purpose of cleaning accumulations of dust and smoke from the precipitator plates, cleaning fluid may be supplied through the pipe 68 controlled by a solenoid valve 69 to a plurality of nozzles 70 by way of a plurality of branch lines 71. The branch lines 71 may be supported in the upper portion of the housing 12 on a pair of rods 72, which rods are in turn supported on ledges 73 formed by welding angle irons on the interior wall of the casing 12. The nozzles 70 are sufficient in number to direct the cleaning fluid, which may be hot or soapy water, to all parts of the ionizing and collector plate assembly. The streamline form of the surface electrodes 45 and 63 also permits the cleaning fluid to reach all surfaces of these electrodes and be deflected through the collector plate assembly.

During operation it may occasionally happen that lumps or agglomerations of dust, dirt, and smoke particles previously precipitated upon the collector plates will become dislodged and fall to the chamber below the collector plate assembly. These agglomerations of dust, dirt, and smoke particles are not to be confused with the unprecipitated impurities originally present in the untreated air, but all of appreciable size and capable of being filtered or otherwise separated from the air stream. In order to prevent such agglomerates from being carried outwardly through the duct 66, I provide an eliminator comprising a plurality of angle irons 77 disposed across the discharge 66 so that the air passing therethrough must move upwardly for at least a short distance. The agglomerated particles are of such weight that they will not ordinarily be drawn upwardly against the force of gravity by the air stream and thus remain in the lower chamber to be washed out upon the next washing operation.

While there has been herein described a preferred embodiment of the invention, other embodiments within the scope of the appended claims will be apparent to those skilled in the art from a consideration of the form shown and of the teachings hereof.

What is claimed is:

1. An electrical precipitator for separating impurities from air and other gases comprising a housing, a combined ionizer and collector plate assembly removably mounted in said housing, said assembly comprising a frame, collector plates and ionizer elements mounted on said frame, and insulators separating said ionizer elements and at least part of said plates from said frame and from each other, means in said housing for supporting said frame therein, and means in said housing for supplying cleaning fluid to said combined ionizer and collector plate assembly to wash accumulations of precipitated matter therefrom.

2. An electrical precipitator for separating impurities from air and other gases comprising a housing, at least one fine wire electrode, and a plurality of collector plates comprising charge plates and ground plates mounted in said housing, at least one of said charge collector plates having a projecting portion integral therewith providing an electrode coating with said fine wire electrode, said projecting portion being formed in a streamlined shape which is substantially cylindrical on the side toward incoming air or other gas and tapered in the direction of flow of said air or other gas, and means insulating said charge plates and said fine wire electrode from said housing and from each other.

3. An electrical precipitator for separating impurities from air and other gases comprising a housing, at least one fine wire electrode, and a plurality of collector plates mounted in said housing, at least one of said collector plates having a projecting portion integral therewith providing a surface electrode coating with said fine wire electrode, said surface electrode presenting a substantially streamlined contour to the flow of air through the precipitator, said contour being substantially cylindrical on the side toward incoming air or other gas and tapered in the direction of flow of said air or other gas, and means in said housing on the upstream side of said collector plates and ionizer electrodes for supplying cleaning fluid to said electrodes and plates to wash accumulations of precipitated matter therefrom.

4. An electrical precipitator for separating impurities from air and other gases comprising a frame, a plurality of spaced, parallel collector plates mounted on said frame, alternate of said plates being electrically insulated from the intervening plates and constituting charge plates, a fine wire electrode insulatedly mounted in said frame, said wire being insulated from said plates, positioned in the gas stream ahead of said collector plates, at least one of said charge plates having a projecting portion extending beyond other of said plates in the direction of the incoming air, said projecting portion having a curved surface providing an electrode coating with said fine wire electrode and presenting a substantially streamlined contour to the flow of air through said precipitator.

5. An electrical precipitator for separating impurities from air and other gases comprising a framework having a pair of opposite side walls, at least one fine wire electrode, and a plurality of spaced, parallel collector plates comprising charge plates and ground plates supported by said side walls and parallel thereto, the charge plate next adjacent at least one of said side walls at the end of said plurality of collector plates

having a projecting portion extending beyond other of said plates in the direction of the incoming air, said projecting portion having a curved surface providing an electrode coating with said fine wire electrode and being spaced from said one side wall, said wire electrode being located on the side of said charge plate opposite from said one side wall, and means positioned on the upstream side of said projecting portion for deflecting air away from the space between said charge plate and said one wall and into the space between said charge plate and said fine wire electrode.

6. In a particle precipitator having an ionizer and a collector plate assembly adapted for the precipitation of ionized particles from a gas passing therethrough, a frame having side-walls parallel to the plates of said assembly, a plate of said assembly adjacent a side wall having a surface lying in the direction of gas flow and extending forward of said assembly toward the oncoming gas, said plate being convexed at the side away from said wall near its forward edge to present on said side a streamlined convex obstruction in the path of said flow, and a baffle mounted on said wall confronting said forward edge on the upstream side thereof positioned to deflect flowing gas to said convexed side and away from the space between said wall and said plate.

7. An electrical precipitator for separating impurities from air and other gases comprising a frame, first and second spaced collector plates mounted in said frame, one of said plates being insulatedly mounted, a fine wire electrode insulatedly mounted in said frame, said wire being insulated from said plates, said insulated plate having a projecting portion extending beyond said collector plates in the direction of incoming air, said portion having a curved surface providing an electrode coating with said fine wire electrode.
